W. GIESSEMAN & C. V. CRIST.

PAPER BOTTLE.

APPLICATION FILED AUG. 12, 1912.

1,076,669.

Patented Oct. 28, 1913.

UNITED STATES PATENT OFFICE.

WILLIAM GIESSEMAN AND CHARLES V. CRIST, OF DAYTON, OHIO, ASSIGNORS TO THE DAYTON PAPER BOTTLE COMPANY, OF DAYTON, OHIO.

PAPER BOTTLE.

1,076,669.

Specification of Letters Patent.

Patented Oct. 28, 1913.

Application filed August 12, 1912. Serial No. 714,544.

To all whom it may concern:

Be it known that we, WILLIAM GIESSEMAN and CHARLES V. CRIST, citizens of the United States, residing at Dayton, in the county of 5 Montgomery and State of Ohio, have invented certain new and useful Improvements in Paper Bottles; and we do declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

Our invention relates to new and useful improvements in sanitary milk bottles.

The object of the invention is to improve the bottle shown and described in our former 20 Patent, No. 1,039,379, of September 24, 1912, by means of a series of diagonal sealing folds at the junction between the tapered portion and upper terminal of the body of 25 the bottle to effectually seal the openings caused by the slits necessary in forming the tapered portion of the bottle.

Before describing our invention in detail, we will first refer to the accompanying drawings of which—

30 Figure 1 is a side elevation of our improved sanitary milk bottle; Fig. 2 is a plan view of the blank from which said bottle is formed; Fig. 3 is a transverse section on the line *a—a* of Fig. 1; Fig. 4 is a transverse 35 section on the line *b—b* of Fig. 1; Fig. 5 is a similar section on the line *c—c* of Fig. 1.

In the description to follow, similar reference characters indicate corresponding parts in the drawings and specification.

40 In the formation of our sanitary paper milk bottle, a single blank 1 of suitable paper is used. This is preferable because it is highly desirable in the construction of such a bottle to avoid the use of more than a single 45 blank of paper because of the possibility of air spaces and inclosed pockets resulting where more than a single blank is used and in which particles of milk might lodge and remain. The bottle so constructed of the 50 blank 1 is octangular in cross section at any point thereof with the exception of the neck. It, therefore, follows that the vertical score lines 2 extend crosswise of the blank and throughout the depth of the portion of the 55 blank forming the lower body 3 and upper

tapered or contracted body portion 4. As shown in Fig. 2, the score lines 2 extend from one extreme edge of the blank to the points 2' which lie immediately on the outer side of the longitudinal or horizontal score 60 line 5. From the points 2' the blank is provided with vertical slits 6 which extend from the points 2' to the extreme edge of the blank. From the longitudinal or horizontal score line 5, other slits 7 are provided 65 which extend diagonally from the slits 6 to said score line 5 and provides a series of triangular sealing folds 11. The manufacture of the paper bottle is greatly facilitated and the character of the bottle greatly improved 70 by extending the vertical score lines 2 from one extreme edge of the blank to the points 2' as indicated. This provides for the body of the bottle being octangular in cross section as before stated and for the sealing 75 folds just referred to. The tapered portion 4 of the bottle lies between the score lines 8 and 5 and is provided for by the formation of the diagonal score lines 9 which provide the triangular folds 10 which lie between the 80 adjacent inner and outer folds when the upper body portion of the bottle is constructed as in Fig. 1. The score lines 9, it will be observed, extend from the score line 8, at the points where the score lines 2 intersect 85 the score line 8, to the inner terminals of the slits 7. The upper ends of the triangular folds 10 terminate at the score line 5, and, owing to the slits 7, triangular folds 11 are provided which form seals for the corners 90 which intervene between the tapered portion of the bottle and the cylindrical neck portion 4' of the bottle. The neck portion of the bottle is formed by the portions 13 of the blank which lie on the outside of the score 95 line 5 and are formed by the slits 6, before referred to. Owing to the contracted character of the neck of the bottle, the portions 13 of the blank overlap throughout the circumference of the neck of the bottle and 100 thus reinforce said neck as is shown in Fig. 3 and thus naturally strengthen this part of the bottle which is usually called upon to stand the greatest strain.

Having thus described our invention, we 105 claim:

A new article of manufacture, comprising a paper bottle constructed from a blank of paper cut and scored to form a body of polygonal form, said blank being provided 110

with vertical score lines which provide for the formation of the body of the bottle, and diagonal and longitudinal score lines which provide for the formation of the tapered portion of the bottle and the neck, the vertical score lines being extended across the longitudinal score lines, and diagonal slits extending from the upper or outermost longitudinal score line to the upper terminals of the vertical score lines and thence to the adjacent edge of the blank in line with the vertical score lines, said diagonal slits form-

ing a series of triangular sealing folds at the intersection of the neck with the tapered portion of the bottle, substantially as described. 15

In testimony whereof we affix our signatures in presence of two witnesses.

WILLIAM GIESSEMAN.
CHARLES V. CRIST.
